UNITED STATES PATENT OFFICE.

WILLIAM W. PEYTON, OF CARLISLE, ARKANSAS.

SHOE-DAUBER,

No. 856,908.

Specification of Letters Patent.

Patented June 11, 1907.

Application filed June 20, 1906. Serial No. 322,616.

To all whom it may concern:

Be it known that I, WILLIAM W. PEYTON, a citizen of the United States of America, residing at Carlisle, in the county of Lonoke 5 and State of Arkansas, have invented new and useful Improvements in Shoe-Daubers, of which the following is a specification.

This invention relates to shoe daubers designed especially for use in connection with liquid blacking bottles, and has for its objects to produce a comparatively simple, inexpensive device of this character which may be conveniently manipulated for applying liquid blacking or paste to the shoes, and one 15 which may be readily handled without soiling the hands of the operator.

A further object of the invention is to provide a novel form of handle for manipulating the dauber, one which serves as a clamp for 20 maintaining the paste applying cloth on the body of the device, and one wherein the bristles forming the daubing brush are effectually secured to the dauber stem or shank.

With these and other objects in view, the 25 invention comprises the novel features of construction and combination of parts more fully hereinafter described.

In the accompanying drawings: Figure 1 is a perspective view of a dauber embodying 30 the invention. Fig. 2 is a side elevation of the same. Fig. 3 is a detail view of the dauber stem.

Referring to the drawings, 1 designates a body portion preferably composed of cork 35 and in the form of a stopper adapted for closing the mouth of the blacking bottle, there being engaged with the body one end of a vertically depending stem or shank 2 preferably composed of wire and having its body engaging end provided with an engaging hook 3 adapted for secure engagement with the material of the body or stopper, while formed at the lower end of the stem is a bristle receiving hook 4 presenting an upwardly opening slot 45 or recess 5 in which the bristles forming the dauber brush 6 are seated, and secured in place by means of a tie element or wire 7 wrapped or coiled around the bristles. It will be understood in this connection that 50 the bristles are, in the formation of the brush, engaged at their longitudinal center in the seat or recess 5 being thereafter folded and tied by means of the wire 7.

For manipulating the device there is provided a handle 8 formed of a single piece or 55 length of wire bent to provide a central

spring clamping portion or coil 9 designed to embrace the body 1 and having a pair of substantially parallel spaced arms, one of which is formed with a terminal engaging portion or hook 10 adapted for engagement with any one of a series of engaging portions or eyes 11 produced at the terminal of the other arm by suitably bending the material thereof into shape, it being noted that the series of engaging portions or eyes 11 are arranged in spaced order and disposed in a plane perpendicularly to the longitudinal axis of the handle.

Employed in connection with the device and for use in applying paste or solid blacking to the shoes is a piece of cloth or other suitable pliable material 12 adapted for application over the upper end of the body or stopper 1 and to be secured in place thereon through the medium of the clamping portion or ring 9, whereby the cloth is removably maintained in place for convenient replacement when desired.

In practice, the stopper 1 is seated in and for closing the neck of a bottle, as usual, and with the brush 6 immersed in the liquid blacking. Under these conditions when it is desired to apply the blacking to a shoe, the arms of the handle are disengaged from each other and the clamping ring 9 seated over the stopper as seen in Fig. 1, after which the handle arms are brought together until the ring is in secure clamping engagement with the stopper, after which the hook 10 is engaged with one of the eyes 11. The handle may then be employed for removing the stopper from the bottle and for holding the device while applying the blacking to the shoe and this without soiling the hands of the operator. When shoe paste or solid blacking is to be applied to the shoe, the cloth 12 is arranged over the end of the stopper and clamped in position thereon through the medium of the ring 9 in the operation of engaging the handle with the body.

Having thus described my invention, what I claim is:

1. A device of the class described comprising a body, a dauber brush having a stem engaged with the body, and a handle having a spring clamping coil designed to embrace and for clamping engagement with the body.

2. A device of the class described comprising a body portion, a dauber carried thereby, a handle having a spring clamping coil designed to embrace the body, a pair of arms

joined to the coil and movable for expanding or contracting the latter, and means for connecting the ends of the arms.

3. A device of the class described comprising a body portion and a dauber carried thereby, and a handle composed of a single piece of material and consisting of a pair of spaced arms joined at one end with a spring clamping coil designed to embrace the body and

provided at their outer ends with interengaging devices for fixing the arms in clamping position.

In testimony whereof, I affix my signature in presence of two witnesses.

WILLIAM W. PEYTON.
